(57) **CLAIM**

The ornamental design for a fingerprint management device, as shown and described.

DESCRIPTION

FIG. 1 is a front view of a fingerprint management device with the subject design;

FIG. 2 is a back view of the fingerprint management device of FIG. 1;

FIG. 3 is a left lateral view of the fingerprint management device of FIG. 1;

FIG. 4 is a right lateral view of the fingerprint management device of FIG. 1;

FIG. 5 is a top view of the fingerprint management device of FIG. 1;

FIG. 6 is a bottom view of the fingerprint management device of FIG. 1;

FIG. 7 is one perspective view of the fingerprint management device of FIG. 1; and,

FIG. 8 is another perspective view of the fingerprint management device of FIG. 1.

One embodiment of the design application is a product with a commercial name “FTSleeve”.

The subject design is to manage fingerprint of a fingerprint card, i.e., collecting, verifying or deleting the fingerprint, etc., and the subject design is applicable to enterprises and individual users.
